UNITED STATES PATENT OFFICE.

LOUIS McCARTHY, OF BOSTON, MASSACHUSETTS.

INSULATOR.

No. 807,307.

Specification of Letters Patent.

Patented Dec. 12, 1905.

Application filed February 18, 1904. Serial No. 194,155.

To all whom it may concern:

Be it known that I, LOUIS McCARTHY, a citizen of the United States, residing at Boston, in the county of Suffolk, State of Massachusetts, have invented a certain new and useful Improvement in Insulators, of which the following is a specification, reference being had therein to the accompanying drawing.

My invention has for its object an improved insulator which shall be especially adapted for use out of doors or in situations where it is to be exposed to moisture.

In the installation of incandescent electric lights for street-lighting and the like the current employed is frequently taken from a line of high potential by the employment of a transformer. In such cases it is desirable that the lamp should be separated from the supporting-bracket or fixture by a strong and durable insulator, which shall be substantially free from moisture throughout at least a considerable portion of its exterior surface and which shall afford thorough insulation against the passage of a powerful current in order that the danger which might result from a current on the lamp side of the fixture passing into the supporting-bracket may be reduced to a minimum.

The invention is fully set forth in the following description, taken in connection with the accompanying drawings, and the novel features thereof are pointed out, and clearly defined in the claims at the close of this specification.

The accompanying drawing illustrates an embodiment of my invention utilized in connection with an incandescent electric lamp and its supporting-bracket intended for out-of-doors use. The said drawing shows, partly in section and partly in elevation, a lamp-socket and portion of a lamp, an insulator embodying my invention, and a portion of a bracket arm or support.

Referring to the said drawing, A designated a portion of a supporting-bracket of common construction, the said bracket-arm being hollow for the passage of the wires 1 and 2, which supply the lamp. The end of the said bracket to which the insulator is attached is screw-threaded, as shown at 3. The lamp is shown at B and its socket at D, these being of any well-known construction. In the form shown the lamp-socket is provided with a threaded sleeve or tubular portion 4, which is adapted for attachment to the insulator. The insulator comprises a mass of molded in-

sulating composition C, which is of the peculiar bell or frusto-conical shape shown and which is provided at the lower and larger end with a skirt 5, projecting downwardly well below the metallic connection of the insulator. Inside of the skirt 5 I provide a short annular projection or skirt 6, separated from the skirt 5 by an intervening crowning or curved contour space 7. On the inside of the short skirt 6 or projection 6 occurs another interval or separate space 8, which separates the said short skirt from the metallic threaded sleeve 9, which is embodied in the mass or body C of insulating material and serves as a secure means of connecting socket-sleeve 4 with the said insulator.

Embedded in the upper end or top of the insulator-body C is a cylindrical metallic piece or sleeve 10, which is interiorly threaded and adapted to be screwed onto the threaded end of a supporting-bracket A. In practice the threaded sleeve or connection 10 is usually considerably larger in diameter than the threaded-sleeve connection 9. The said metallic sleeves 9 and 10 are at the opposite ends of a hole or passage 11, which is located centrally of the mass of insulating material C and which affords ample accommodation for the lamp-supply wires 1 and 2, thus greatly facilitating the attachment of the lamp-socket to the wires 1 and 2 and to the insulator. If the passage 11 is not of ample size, it does not afford room for any extra length of wires 1 and 2, which requires to be pulled out in order to make proper attachment with the socket. The said passage, therefore, not only serves as a means of permitting the wires to pass through the insulator, but also as a receptacle for the surplus wire which is required, and the presence of which permits a better and much more speedy adjustment of the lamp-socket by the operator who is installing or repairing the construction. The surplus length of wires 1 and 2 above referred to is indicated by the coiled or bent portions thereof at 12 and 13.

In connection with the lamp-socket a reflector or other similar device of common construction (not shown) may be employed, as will be clear.

The conical or tapering shape of the body of the insulator C carries descending moisture well away from the metallic parts at the lamp end of the insulator, and the skirt permits it to drip from the insulator and prevents it creeping upwardly on the inside of

the skirt. The slight moisture which may collect by deposition is shed by the inner skirt 6 and prevented from passing to the metallic sleeve 9 of the insulator with which the 5 lamp-socket is connected. The peculiar double-skirt construction with the crowning-space 7 between the skirts I have found to be particularly advantageous in practice in insuring a dry under body, and thus preventing 10 or reducing to a minimum the danger of a current passing over the exterior surface of the insulator between the lamp-socket and the supporting-bracket.

What I claim is—

15 An insulator comprising a body portion of molded composition having formed thereon one or more skirts or projections for the shed-

ding of moisture, and having an opening therethrough to permit the passage of supply-wires of a size sufficient for the reception of surplus wires, and independent metallic-sleeve connections insulated from each other at each end of said opening and forming a continuation thereof, said metallic connections being molded into said body portion and serving as 20 a means of attaching the said insulator to the contiguous portions of the construction. 25

In testimony whereof I affix my signature in presence of two witnesses:

LOUIS McCARTHY.
